Primary Examiner — Ian Simmons*Assistant Examiner* — Keith Frank(74) *Attorney, Agent, or Firm* — Tai W. Nahm; Miller Thomson LLP(57) **CLAIM**

The ornamental design for a bottle, as shown and described.

DESCRIPTION

FIG. 1 is a top right perspective view of a bottle showing our new design;

FIG. 2 is a front elevation view thereof;

FIG. 3 is a rear elevation view thereof;

FIG. 4 is a left elevation view thereof;

FIG. 5 is a right elevation view thereof; and,

FIG. 6 is a top plan view thereof.

The broken lines in the drawings showing the bottle illustrate the portions of the bottle that form no part of the claimed design.
